UNITED STATES PATENT OFFICE.

ARTHUR J. LEONARD, OF OIL HILL, KANSAS, ASSIGNOR TO DCHEERY RESEARCH COMPANY, OF NEW YORK, N. Y., A CORPORATION OF DELAWARE.

DERRICK.

Application filed September 15, 1923. Serial No. 662,801.

This invention relates to derricks of the type which are commonly used for drilling oil wells.

Most of the different forms of derrick construction particularly wooden derricks, are such that when the derrick has been used for drilling a well and pumping oil there are few parts of it which can be again used for building a new derrick. The construction has been such that the derrick soon becomes loose in the joints so that companies have been required to periodically repair the derricks, tighten all joints and splices in order to keep them rigid for reliable operation. This practice is especially necessary in the parts of this country where high winds prevail and at these places it is often very necessary to anchor the derrick with an extensive system of guy wires. Furthermore, the new methods of drilling have necessitated the use of higher and stronger derricks.

The primary object of the present invention is to provide a derrick construction by which a derrick may be maintained sufficiently rigid for all purposes and which may be readily disassembled, transported and reassembled for use in another place.

A further object of the invention is to provide a derrick construction by which unit parts of a derrick may be built in a factory to insure good construction and to assist in the rapid assembly of a derrick.

Other objects and features of the invention consist in the particular arrangement and combination of parts hereinafter described and claimed.

The various features of the invention are illustrated in the accompanying drawings in which

Fig. 1 is a top plan view of a derrick according to my invention;

Fig. 2 is an elevation of the upper portion of the derrick appearing in Fig. 1;

Fig. 3 is an elevation of the lower portion of the derrick appearing in Figs. 1 and 2 taken looking in the same direction as in Fig. 2;

Fig. 4 is an elevation of the lower portion of the derrick taken at right angles to Fig. 3;

Fig. 5 is a detail taken on the line 5—5, of Fig. 2 looking in the direction of the arrows;

Fig. 6 is an interior perspective of a joint

in one of the legs or longitudinals of the derrick illustrated in Figs. 2 and 3;

Fig. 7 is a detail view partly in section illustrating the method of attaching the ladder to the derrick in accordance with the invention;

Fig. 8 is a plan view of a horizontal strut or girt used in the derrick illustrated in Figs. 2 and 3;

Fig. 9 is an end elevation of the strut shown in Fig. 8;

Figs. 10 and 11 are elevations taken in opposite directions of one of the outside angle plates appearing in Figs. 2 and 3;

Figs. 12 and 13 are elevations taken in opposite directions of one of the inside angle plates used in building derricks according to the invention and illustrated in position in use in Fig. 6.

Referring to the drawing in detail, the preferred form of derrick comprises a plurality of longitudinals or legs 14—14 placed at the corners of the structure. The legs 14 are made of solid timbers framed in relatively short sections, the joints between adjacent sections being covered and reinforced by outside angle plates 16, 16, and also by inside angle plates 18, the angle plates being clearly illustrated in Figs. 6 and 10 to 13. The adjacent ends of sections of the legs 14 are connected together by being bolted through both the outside and inside angle plates by two pairs of bolts 20, 20 running at right angles to each other. The structure is stiffened and strengthened by horizontal struts or girts 22, 22 of which there is one between each two adjacent legs at each joint between the sections of the legs 14. Each of the girts 22 comprises a strip 23 fastened to the angle plates 16 at each end by means of U-bolts 24, 24. The U-bolts 24 are long enough to completely embrace the width of the elements 23 and pass through holes in the outside angle plates 16 at the edges of the strips 23. Girts 23 comprise also longitudinal stiffening ribs 26, 26, bolted to strips or elements 23. The planes of the ribs 26 lie substantially at right angles to the planes of the elements 23 and the girts rest at both ends against the inner angle plates covering the joints in the legs 14. The ribs 26 are cut away as illustrated at 27 (Fig. 8) to permit the U-bolts 24 to be slipped into place. The girts 22 are placed under compression by diagonal ties or braces 28, 28 extending from

110

the outside angle plates 16 to the angle plates of the joint in the legs next above or below the joint under consideration. The ties 28 are connected to outside angle plates 16 by a keyhole joint. These joints comprise elongated slots 30, 30 cut through the outside angle plates 16 near the corners and extending diagonally. The slots 30 are enlarged at their ends nearest the corner of plates 16, illustrated at 31 in Fig. 6. The ties 28 are bent at right angles to their length at their ends and have their ends enlarged as illustrated at 29, Figs. 5 and 6. Therefore when the enlarged ends 29 of the ties 28 have been slipped through the enlargements 31 of the slots 30 the smaller portion of the bent ends of the rods 28 may be readily slipped down into the narrow portions of the slots 30. The ties 28 being now placed under tension, the ties 28 are securely connected to the plates 16 at each end so long as the ties remain under tension, but it is evident that the ties may be readily disconnected from the plates whenever the tension is released. It is evident that the form of connection just described utilizing slots 30 of keyhole form in plates 16 dispenses with all loose parts such as washers, nuts, and the like. The ties 28 are conveniently placed under tension after being placed in plates 16, as just described, by turnbuckles 32. The turnbuckles 32 are preferably located in the centers of the ties 28 so that flattened portions 34 in the mid parts of the turnbuckles 32 of two crossing braces will contact with one another. The parts 34 are slotted as indicated at 36 so that when the parts are assembled and under tension and brought into contact as illustrated in Fig. 5 bolts 38, 38 are passed through the slots 36 in adjacent turnbuckles 32 and the two fastened securely together. It is evident from the foregoing as applied to the drawing, that when the ties 28 are placed under tension by the turnbuckles 32, the girts 22 are thereby placed under compression and the structure of the girts 22 with the manner of assembling the same as previously described, permits very considerable pressure to be placed on the girts thereby making the entire structure very rigid when in use. Further when the tie braces are locked by the bolts 38 they cannot work loose.

The major portion of the derrick according to my invention is made by assembly of the parts previously described, but the top and bottom ends of the derrick according to my invention are somewhat differently constructed. It is advantageous to make the top portion stronger than necessary for the intermediate portions and at the extreme upper ends of the legs 14 I provide special outer angle plates 39, 39 having slots 30 in their lower corners to provide connections for the ties 28 running to the angle plates 16 at the first joint below the top. The plates 39 are

also drilled to receive bolts 20 connecting them to the upper ends of the legs 14. Plates 39 are vertically longer than plates 16 and extend up above the upper ends of the legs 14 into engagement with heavy crown timbers 40, 40. The edges of the timbers 40 rest on the upper ends of the legs 14 and the ends of the timbers 40 are framed together at 41 and form a square frame all as illustrated in Fig. 1. Timbers 40 are firmly connected together and to the plates 39 by a plurality of bolts 42, 42 extending between pairs of opposite timbers 40. It is evident that the structure at the upper end of the derrick is very strong and the ends of the legs 14 are not only securely connected together but are also protected against damage.

In addition to the structure just described at the extreme upper end of the derrick, I prefer to provide also special reinforcing means at the tops of the legs comprising two auxiliary braces 44, 44 on each face of the derrick, each pair of braces 44 being beveled at their upper ends as illustrated at 45 (Fig. 2) and securely bolted to one of the timbers 40 by bolts 46, 46. From the timbers 40 each pair of braces 44 extends downwardly a distance equal to two sections of the legs or corner posts 14 and are secured to the two girts 22 across which they extend by bolts 48, 48. Preferably, as illustrated in Fig. 2, the angle between each pair of auxiliary legs 44 is somewhat greater than that between two corner legs 14 so that the lower ends of the braces 44 are secured to the second girt from the top of the derrick closely adjacent to the angle plate 16 connected to this particular girt. I find that this arrangement materially increases the stiffness of the upper portions of the derrick.

Referring now more particularly to Figs. 3 and 4, the portion of the derrick according to my invention which is next the ground or foundation is made differently from the intermediate portions of the derrick in order that the ties and braces shall not interfere with the drilling operations or other matters with which the workmen are engaged. For this reason, the lower sections 15, 15 of the legs 14 are made longer than those above, and securely connected together at their lower ends by horizontal timbers 52, 52 so placed near the tops and bottoms of the sections 15 as to interfere as little as possible with the work to be done. Two adjacent ones of the lower leg sections 15 moreover are particularly selected as the starting and wind-resisting legs and are braced in two directions in the planes of legs 14, 14 by struts 54, 54 (Figs. 3 and 4). The struts 54 are connected to their corresponding legs-sections 15 at the bottom by pieces 56 and members 54 and 15 are further connected by horizontal braces 58 and diagonal braces 60. Braces 58 are arranged

horizontally near the mid portions of members 15 and 54 and are formed of timbers fitted in between the said members and securely connected thereto by bolts 62 extending entirely through the length of the members 58 and through the sides of the members 15 and 54. The diagonal braces 60 are below the braces 58 and braces 60 are also made of timbers fitted carefully between the members 15 and 58 but are secured thereto by bolts 64, 64 passing through the respective members at the ends of braces 60. Wherever it is necessary to run moving members through the sides of the derrick, such members for instance, as walking beams or ropes subject to vertical oscillation a special construction is necessary. One such specially constructed portion is illustrated in Fig. 3 and comprises in addition to the usual sections of the legs 14 and the girts 22, a pair of parallel spaced struts 66, 66, one on each side of the line connecting the centers of two adjacent girts 22. The struts 66 connect at each end with special plates 68, 68 fastened to the girts 22 and the plates 68 are firmly connected by pairs of short diagonal ties or braces 70, 70 to the outside angle plates 16 at the ends of the girts to which the struts are connected.

It is necessary for the use of a derrick to have a ladder associated with the same, and according to my invention, I provide a ladder which can be placed in position on the derrick and removed therefrom with a minimum of trouble, when desired, but which is firmly and securely connected to the derrick when in use.

Referring now more particularly to Figs. 1, 2, 4 and 7, 72 is a ladder formed in sections, the ends of adjacent sections abutting the joints between adjacent sections being arranged to fall on one of the horizontal struts or girts 22 of the derrick structure. The lower ends of the sections of ladder 72 have secured thereto pins 74 fastened on the inside faces of the ladder sections and bent away from members 76 so that the free ends of the pins lie parallel to the longitudinal members 76 of the ladder leaving space enough between the free ends of the pins 74 and the members 76 to receive the outer element 23 of the girts 22. Preferably also the ribs 26 of girts 22 are apertured as illustrated at 78 in Fig. 7 to receive the free ends of pins 74, these being long enough to pass not only through apertures 78, but also through apertures in the outwardly bent ends of straps 75 fastened to the next lower ladder section, and the ladder sections are thus securely hooked to the girts 22. Adjacent ladder sections moreover may be firmly hooked together by hooks 80 carried on the outside of the longitudinals 76 and engaging eyes 82 on the adjacent sections.

The derrick construction illustrated and described above permits the building of a number of units in the factory which permits the parts to be inspected and carefully built and allows the units to be used for a rapid assembling of a derrick. For example, the posts 14 with plates 16 bolted to their ends are assembled in the factory. All of the units 22 are assembled in the factory. The crown timbers for the top of the derrick are assembled in the factory. The ladders are assembled in the factory. The brace sections 15 are assembled in the factory and, in fact, the entire derrick is framed and parts arranged and distinguished so that it is a mere matter of bolting them together when the derrick is assembled. This has a great advantage because it allows the perfect construction to be maintained notwithstanding that in many cases derricks are constructed in isolated places where it is not possible to have good working conditions and to secure the services of the highest grade mechanics.

It is evident that all the parts forming a derrick above described may be readily connected and disconnected when desired. Also all connections are made exclusively by bolts so that no part is damaged in disconnecting. The same parts can therefore be used again and again as there is need for using a given derrick in different places. A part, however, which has been accidentally damaged, either in use or in transportation may be readily replaced without lessening the utility of the remaining parts.

Derricks constructed as above described have shown high rigidity and strength both as regards the stresses produced by drilling or like operations and those caused by high winds.

Having thus described my invention, what I claim is:

1. In a derrick having upright corner posts, the combination of angle irons secured to the posts, girts secured to the angle irons, turn-buckle tie rods secured to diagonally opposite angle irons, the turn-buckles on adjacent tie rods being arranged side by side in contacting relation whereby they normally mutually oppose relative turning.

2. In a derrick having upright corner posts, the combination of angle irons secured to the posts, girts secured to the angle irons, tie rods secured to diagonally opposite angle irons, length-adjusting means on the tie rods, said means on one tie rod normally abutting the similar means on an adjacent tie rod whereby relative turning of said means is mutually opposed by reason of their abutting relationship.

3. In a derrick having upright corner posts, the combination of angle irons secured to the posts, girts secured to the angle irons, tie rods secured to diagonally opposite

angle irons, length-adjusting means on the tie rods disposed in opposition to the similar means on an adjacent tie rod each of said means having a flat side, the said sides of adjacent means being arranged side by side whereby to mutually oppose relative turning of said means.

4. In a derrick having upright corner posts, the combination of angle irons secured to the posts, girts secured to the angle

15
iron, turn-buckle tie rods secured to diagonally opposite angle irons, the turn-buckles having openings extending transversely therethrough, the turn-buckles on adjacent tie rods being arranged side by side, and securing means passing through the openings in adjacent turn buckles.

In testimony whereof I affix my signature.

ARTHUR J. LEONARD.
